FLUID MOTOR VALVE CONSTRUCTION

Thomas Marvin Hardesty, Crockett, Calif.

Application June 27, 1949, Serial No. 101,615

5 Claims. (Cl. 121—164)

1

The present invention has for its primary object the provision of a novel and improved hydraulically operated pump assembly capable of use at the bottom of oil wells for pumping oil.

Among the other objects of my invention are:

(1) To provide a novel and improved hydraulically operated pump assembly for pumping oil from wells, which may utilize a portion of the pumped oil as the hydraulic operating fluid to the pump motor;

(2) To provide a novel and improved reciprocating type hydraulically operated pump assembly adapted for use in oil wells;

(3) To provide a novel and improved reciprocating type hydraulically operated pump assembly in which the probability of the piston stopping on a dead center position is eliminated;

(4) To provide a novel and improved reciprocating type hydraulically operated pump assembly adaptable for use in oil wells, and means in cooperation therewith for utilizing existing gas pressure in a well for assisting such pump assembly in pumping oil from a well.

Additional objects of my invention will be brought out in the following description of a preferred embodiment of the same, taken in conjunction with the accompanying drawings wherein—

Figure 1 is a longitudinal view in section through the upper portion of the pump assembly;

Figure 1a is a corresponding view in a plane normal to that of Figure 1;

Figure 2 is a longitudinal view in section through the intermediate portion of the pump assembly and in the same plane as Figure 1;

Figure 2a is a corresponding view in the same plane as Figure 1a;

Figure 3 is a longitudinal view in section through the lower end portion of the pump assembly and in the same plane as Figure 2;

Figure 3a is a corresponding view in the same plane as Figure 2a;

Figure 4 is a view in section in the plane 4—4 of Figure 1a;

Figure 5 is a view in section in the plane 5—5 of Figure 1a;

Figure 6 is a view in section in the plane 6—6 of Figure 2a;

Figure 7 is a view in section in the plane 7—7 of Figure 2a;

Figure 8 is a view in section in the plane 8—8 of Figure 3a;

Figure 9 is a view in section in the plane 9—9 of Figure 3a;

2

Figure 10 is a view in section in the plane 10—10 of Figure 3a;

Figure 11 is a view in section in the plane 11—11 of Figure 3a;

5 Referring to the drawings for details of my invention in its preferred form, the same, for convenience of analysis and description, may be divided into two parts, namely the pump 1 and the hydraulic motor 3 which drives such pump. 10 Both portions, however, are intimately connected into a unitary pump assembly capable of being lowered down to the bottom of a well for pumping oil therefrom to the surface.

The entire pump assembly in general is formed 15 of a plurality of blocks, namely a head block 5, an intermediate block 7 and a lower end block 9 held in spaced relationship longitudinally by cylindrical casing sections 11 and 13 of similar diameter. This gives to the entire assembly a uniform 20 outside diameter free of projections, thereby enabling the same to slide freely down a bore to the bottom of a well.

The pump portion which is formed in the lower 25 half of the assembly, involves a cylinder 15 of smaller diameter than the casing section, such cylinder being fixed at its ends within the intermediate block 7 and the lower end block 9 of the assembly. This creates a spacing 17 between the cylinder and the associated casing section which 30 constitutes a part of the discharge for the oil pumped by the pump.

The lower end block is provided with an off-center bore 19 extending longitudinally therethrough, in which is fitted an intake and discharge ball valve assembly 21 involving a tube 23 35 having spaced valve seats 25 and 27 on each of which rests a ball valve 29. A pin 31 diametrically disposed above each ball valve, limits the permissible movement of each such valve from its seating position.

40 From a location intermediate the ball valves, there is a connecting passage 33 to a central bore 35 in the lower end block, connecting with the cylinder of the pump. The ball valve assembly is held in the off-center bore by an open nut 37 45 threaded into the lower end of said bore.

In the cylinder of the pump, is a piston 39 adapted for reciprocal movement therein, and having a piston rod 41 extending upwardly 50 through an enlarged central passage 42 through the intermediate block, into the motor end of the pump assembly.

The intermediate block, like the lower end block, is similarly provided with an off-center bore 43 therethrough, in which is mounted a

55

similar intake-discharge ball valve assembly 45 supported at its lower end by a closure plug 46. The bore has an intake passage connection 47 from the outside, while intermediate the ball valves, a connecting passage 49 leads to the cylinder of the pump by way of the enlarged piston rod passage 42, whereby on the intake stroke of the pump, liquid will be suctioned into the upper end of the pump cylinder, and during the return stroke, will be discharged through the upper ball valve of the valve assembly 45.

The pump as thus described is a double acting pump adapted to suction in and discharge liquid on both the forward and return strokes of the pump piston.

If in certain designs, it is found necessary to use a smaller size ball valve assembly at the upper end of the pump by reason of the enlarged piston rod passage leading to the pump cylinder, it is contemplated that a plurality of such ball valve assemblies may be installed, each with its own connection to the passage leading to the pump cylinder.

At the motor end of the hydraulic pump assembly, the aforementioned piston rod terminates in a piston 51 which is slidably disposed in a cylinder 53 which itself is slidably disposed for limited movement within a fixed sleeve 55 of smaller diameter than the casing section and anchored in the head block at one end and in the intermediate block at the other end.

The cylinder is formed with a thicker wall section at each end, resulting in a shoulder 57 at each end facing the piston. Disposed within the motor cylinder, intermediate each such shoulder and the piston, is a floating spring 59 to absorb the impact of the piston as it approaches the end of each stroke. The spring serves to accumulate the energy of such impact for sudden release against the adjacent shoulder of the cylinder.

The motor cylinder has an intake port 61 and a discharge port 63 at each end thereof, and the fixed sleeve has openings 65 and 67 therein which are adapted to alternately expose the ports at each end of the cylinder as the cylinder moves relative to the sleeve within its permissible limits of movement.

In order to isolate the intake ports from the discharge ports of the motor cylinder, and provide for an intake passage 69 to such intake ports, and a separate discharge passage 71 leading from the discharge ports of the pump motor, the cylindrical space between the fixed sleeve 55 and the associated casing section 11 is divided off by radial partitions 73 and 75, so located that the discharge from the upper end of the pump will enter the discharge passage 71 of the motor. As for the discharge from the lower half of the pump, a bore 76 longitudinally through the intermediate block, serves to complete a flow path from the off-center bore 19 by way of the spacing 17 to the discharge passage 71, where mingling of all the pumped fluid with the exhaust fluid of the motor can take place.

To feed the operating fluid to the pump motor and at the same time to provide for discharge of the fluid from the pump assembly, the head block 5 is provided with diametrically disposed bores 77 and 79, one for use as part of the intake passage, and the other for use as part of the discharge passage of the pump assembly.

At its upper end, the head block is provided with a capping pipe section 81 to which may be

coupled, as by a coupling collar 83, the lowermost section 85 of a pipe extending down from the surface. Concentrically disposed within this pipe, is a pipe 87 of smaller diameter, terminating at the head block in a flared section 89 which encompasses but one of the diametrically disposed bores through the head block namely the bore 77. With such arrangement, one of the concentric pipes may be employed to feed operating fluid to the pump motor, while the other pipe may be employed to receive the combined discharge of the pump motor and pump for conduction to the surface above.

The operating fluid pumped down to the well, thus will enter the exposed intake port in the cylinder and drive the piston ahead of it until the piston abuts the shoulder at the other end of the cylinder and forces the cylinder to a position where the aforementioned intake port is closed and the intake port at the far end of the cylinder is opened, with a similar but reverse change taking place in connection with the discharge ports of the cylinder. In this manner, the pump motor is prepared for a return stroke and the operation is thus cyclically repeated to impart action to the pump at the lower end of the assembly.

As thus far described, however, the possibility prevails that the pump motor may stall at a dead center position, that is, with equal portions of the intake ports exposed, whereby pump operations would necessarily cease. To preclude such possibility, and this constitutes an important feature of applicant's invention, means are provided which will preclude shifting of the motor cylinder 53 until the piston impact pressure, as interpreted by the spring 59, reaches such value as to assure carrying the cylinder beyond the dead center position by the momentum thus imparted to it.

In accomplishing this objective, the cylinder is provided with a cylindrical stem 91 at its upper end which is slidably receivable in a longitudinal cylindrical recess provided for the purpose in the head block.

This cylindrical stem is provided with diametrically disposed grooves 93 at an intermediate location thereon, each such groove terminating in a substantially semi-circular recess 95 adapted to snugly receive a roller 97 associated with a latching assembly 99 mounted within the head block. Each such latching assembly comprises a substantially cylindrical cage 101 open at each end but divided transversely by a partition wall 103. Within one end of the cage is mounted the aforementioned roller on a suitable shaft 105 carrying a ball bearing race on which the roller may freely rotate, and the cage is slidably positioned within a bore formed in the head block, the roller facing one of the grooves in the stem. A recessed nut 107 encircling the outer end of the cage and threaded into the head block, provides with the cage, a chamber for a compression spring 109 which serves to resiliently urge the cage and roller in the direction of the stem, whereby the roller will be spring-urged into the groove at all times. The rating of the spring in each of the latching assemblies will of course determine the impact pressure which the piston must exert, to bring about a shift of the cylinder from one stroke-determining position to the other.

In order to preclude entrapment of liquid between the upper end of the cylinder and the head block, and between the upper end of the cylinder

stem and the head block, which could block the upper stroke movement of the cylinder, I provide escape means for such liquid. In the upper end of the cylinder, this may take the form of a bore 111 extending through the upper end wall of the cylinder, while a pair of diametrically disposed channels 113 running the full length of the longitudinal cylindrical recess in which the stem slides, effect a connection with the end of said recess and provide the escape means for any liquid which might otherwise be trapped above the end of this stem.

In some oil wells, there exists considerable gas under pressure, and my improved hydraulic pump assembly is so designed as to take advantage of any such gas pressure to assist the pump assembly in elevating the oil to the surface. This is accomplished through the very simple expedient of installing a ball valve preferably of the check valve type, in a passage which affords communication between the region of gas pressure and the discharge passage of the pump assembly.

Specifically and with reference to the drawings, such passage 115 is provided through the collar 83 in which passage is installed a ball check valve 117 adapted to open under gas pressure of a value which would afford some assistance in elevating the pump discharge to the surface above. In the absence of such gas pressure, the ball check valve will serve normally to block such passage against leakage of oil being discharged from the pump.

From the above description of my invention in its preferred form, it is apparent that the same will fulfill all the objects previously recited, and while I have disclosed the same in its preferred form and in considerable detail, the specific embodiment illustrated and described is subject to alteration and modification without departing from the fundamental principles involved, and I accordingly do not desire to be limited in my protection to the specific details illustrated and described except as may be necessitated by the appended claims.

I claim:

1. A hydraulic motor comprising a cylinder, said cylinder having both an intake port and a discharge port at each end; a piston reciprocally disposed in said cylinder; means for alternately closing the ports at each end of said cylinder both with respect to each other and with respect to the corresponding ports at the other end of said cylinder, in timed relationship to the strokes of said piston, said means involving a sleeve in which said cylinder is relatively slidable within fixed limits, said sleeve having openings therein adapted to alternately expose the ports at each end, as such cylinder moves relative to said sleeve within such limits of movement; means for causing movement of said cylinder relative to said sleeve in response to strokes of said piston said means including a resilient element intermediate each end of said sleeve and said piston; and releasable means resistively holding said cylinder against such relative movement in either direction until the piston impact pressure against an end of said sleeve by way of one of said resilient elements reaches a predetermined magnitude sufficient to overcome said releasable means whereby to permit said resilient element to cast said sleeve through its dead center position and effect the desired reversal of port openings.

2. A hydraulic motor comprising a cylinder, said cylinder having both an intake port and a

discharge port at each end; a piston reciprocally disposed in said cylinder; means for alternately closing the ports at each end of said cylinder both with respect to each other and with respect to the corresponding ports at the other end of said cylinder, in timed relationship to the strokes of said piston, said means involving a sleeve in which said cylinder is relatively slidable within fixed limits, said sleeve having openings therein adapted to alternately expose the ports at each end, as such cylinder moves relative to said sleeve within such limits of movement; means for causing relative movement between said cylinder and said sleeve in response to strokes of said piston, said means including a shoulder on said cylinder at each end thereof and extending into the path of movement of said piston, and a coil spring disposed between each such shoulder and said piston; and releasable means resistively holding said cylinder against such relative movement in either direction during compression of a spring until the piston impact pressure against a shoulder reaches a predetermined magnitude sufficient to overcome said releasable means, whereby to permit said spring to expand and cast said sleeve through its dead center position and effect the desired reversal of port openings.

3. A hydraulic motor comprising a cylinder, said cylinder having both an intake port and a discharge port at each end; a piston reciprocally disposed in said cylinder; means for alternately closing the ports at each end of said cylinder both with respect to each other and with respect to the corresponding ports at the other end of said cylinder, in timed relationship to the strokes of said piston, said means involving a stationary sleeve in which said cylinder is slidable within fixed limits, said sleeve having openings therein adapted to alternately expose the ports at each end, as such cylinder moves relative to said sleeve within such limits of movement; means for causing movement of said cylinder relative to said sleeve in response to strokes of said piston, said means including a shoulder on said cylinder at each end thereof and extending into the path of movement of said piston, and a coil spring disposed between each such shoulder and said piston; and releasable means resistively holding said cylinder against movement in either direction during compression of a spring until the piston impact pressure against a shoulder reaches a predetermined magnitude sufficient to overcome said releasable means, whereby to permit said spring to expand and cast said sleeve through its dead center position and effect the desired reversal of port openings.

4. A hydraulic motor comprising a cylinder, said cylinder having both an intake port and a discharge port at each end; a piston reciprocally disposed in said cylinder; means for alternately closing the ports at each end of said cylinder both with respect to each other and with respect to the corresponding ports at the other end of said cylinder, in timed relationship to the strokes of said piston, said means involving a sleeve in which said cylinder is relatively slidable within fixed limits, said sleeve having openings therein adapted to alternately expose the ports at each end, as such cylinder moves relative to said sleeve within such limits of movement; means for causing relative movement between said cylinder and said sleeve in response to strokes of said piston, said means including a shoulder on said cylinder at each end thereof and extending into the path of movement of said piston, and

a coil spring disposed between each such shoulder and said piston; and means for holding said cylinder against such movement in either direction until said piston approaches either extreme of its stroke and the corresponding coil spring is compressed.

5. A hydraulic motor comprising a cylinder, said cylinder having both an intake port and a discharge port at each end; a piston reciprocally disposed in said cylinder; means for alternately closing the ports at each end of said cylinder both with respect to each other and with respect to the corresponding ports at the other end of said cylinder, in timed relationship to the strokes of said piston, said means involving a stationary sleeve in which said cylinder is slidable within fixed limits, said sleeve having openings therein adapted to alternately expose the ports at each end, as such cylinder moves relative to said sleeve within such limits of movement; means 15 for causing movement of said cylinder relative to said sleeve in response to strokes of said piston, said means including a shoulder on said cylinder at each end thereof and extending into

the path of movement of said piston, and a coil spring disposed between each such shoulder and said piston; and means for holding said cylinder against such movement in either direction until said piston approaches either extreme of its stroke and the corresponding coil spring is compressed.
